US00D979927S

(12) **United States Design Patent** (10) **Patent No.:** **US D979,927 S**
(45) **Date of Patent:** **** Mar. 7, 2023**

(54) **PERSONAL CARE KIT**

(71) Applicant: **Medline Industries, LP**, Northfield, IL (US)

(72) Inventors: **Joseph Bryzek, Jr.**, Kenosha, WI (US); **Paige Wexler**, Highland Park, IL (US); **Angela Zuick**, Northlake, IL (US); **Courtney Mercurio**, Schaumburg, IL (US)

(73) Assignee: **Medline Industries, LP**, Northfield, IL (US)

(**) Term: **15 Years**

(21) Appl. No.: **29/820,350**

(22) Filed: **Dec. 21, 2021**

Related U.S. Application Data

(62) Division of application No. 29/714,204, filed on Nov. 21, 2019, now Pat. No. Des. 941,571.
